COMBINED STABILIZING AND GAS CONVER-
SION PROCESS

Malcolm P. Youker, Bartlesville, Okla., assignor
to Phillips Petroleum Company, Bartlesville,
Okla., a corporation of Delaware

Application July 5, 1933, Serial No. 679,116

9 Claims. (Cl. 196—10)

This invention relates to the manufacture of stable motor fuel from very volatile hydrocarbon liquids and gases such as are contained in natural gas and in the gases which result from the cracking of oils. An object of the invention is to provide a process by which a mixture of hydrocarbon materials, at least a substantial portion of which is sufficiently stable to be incorporated in motor fuel having a boiling point above 100° F. and a portion of which is of lower boiling range and too volatile to be incorporated in motor fuel, may be treated to simultaneously convert a portion of the more volatile material to less volatile material of high anti-knock value and a portion of the less volatile material to material of similar volatility but of higher anti-knock value and to rectify and stabilize the resulting products. Other objects of the invention will be made apparent in the following discussion.

20 My new process may be understood from the description given below which refers to the accompanying drawing on which a form of apparatus, by which my process may be carried out, is illustrated in side elevation.

25 In my co-pending application, Serial No. 610,513, Patent No. 2,040,455, granted May 12, 1936, I have disclosed a process whereby raw unstable liquefied gases may first be rectified in a fractionating column to obtain a fraction of suitable volatility for inclusion directly into motor fuel while at the same time the more volatile fractions separated in the column may be passed through a conversion tube wherein a portion of the more volatile material is converted to material of lower volatility suitable for inclusion in motor fuel and discharged into the same column so that simultaneous rectification of the converted material and the raw material is accomplished and the portions of both suitable for motor fuel 40 may be withdrawn together from the column. By such a process no conversion of the less volatile constituents of the raw charge takes place. By my present process I propose to pass the entire raw liquefied gas through a conversion tube so 45 that the portion which is of suitable volatility for motor fuel will also undergo conversion reactions which will improve its anti-knock value while at the same time the more volatile portions 50 are being converted to less volatile material suitable for conversion to motor fuels. The entire converted material is then rectified, the portion suitable for stable motor fuel withdrawn from the process, the fixed gases discharged from 55 the process and the portions too volatile for motor

fuel but capable of a further conversion are returned to the conversion tube.

Referring to the drawing in one method of operation, unstabilized natural gasoline having a substantial portion boiling over 100° F. will be 5 pumped by a pump 2 through a pipe 1, in which is mounted a valve 4 into and through a conversion tube 5, which leads through a furnace 6, and into a fractionating column 12. A burner 1 supplies the means for heating the furnace 6. The 10 material passing through the conversion tube 5 will be heated to conversion conditions in the furnace 6. A back pressure valve 10 is mounted in the outlet of the tube 5 to permit maintaining the materials undergoing conversion under any 15 desired pressure. The heated converted materials, after passing through valve 10, will pass into an intermediate portion of a fractionating column 12 which is equipped with bubble trays 11. Upon entering the fractionating column 12, 20 the converted materials are in a partially vaporized state, and will separate into a vapor and a liquid portion. The vapors will travel upward through the column 12 over the bubble trays 11 and those reaching the top of the column 12 will 25 pass therefrom through a pipe 20 which leads through a condenser 21 and delivers into an accumulator 22. A portion of the vapors which pass through the pipe 20 and condenser 21 will 30 be condensed therein and as a result a mixture of gases and liquids will flow from the pipe 20 into the accumulator 22. Fixed gases which will 35 accumulate in the accumulator 22 will be discharged through a pipe 23 in which is mounted a back pressure valve 24. A portion of the liquid which will collect in the accumulator 22 will be 40 delivered therefrom through a pipe 25 in which is mounted a valve 26 into the upper part of the fractionating column 12 and will flow thence 45 downward over the bubble plates 11 therein and will contact thereon and condense a portion of the vapors which rise through the fractionating column 12 and the condensate thus produced will 50 flow downward through the column 12 over the bubble plates 11. A portion of this condensate which will flow downward will be withdrawn from the column 12 through a pipe 27 in which is mounted a valve 28 and which is connected into the column 12 at a point intermediate the points of entry of the pipe 5 through which the conversion materials enter the column 12 and the pipe 26, through which reflux material is delivered to the column 12. The quantity of reflux liquid delivered through the pipe 26 into the upper part 55 of the fractionating column 12 will be so regu-

lated as to condense within the column 12 that portion of the vapors which rise through the fractionating column 12 which have a vapor pressure sufficiently low to satisfy the requirements 5 for the liquids obtained from the process. Increasing the quantity of liquid refluxed will increase the vapor pressure of the liquid obtained from the column 12 through the pipe 21 and vice versa. The gravity and end point of the liquid 10 obtained through the pipe 21 will be regulated by regulating the quantity of liquid so obtained and increasing the quantity of liquid so obtained will raise the end point of such liquid and vice versa. Liquid materials heavier than those with- 15 drawn through the pipe 21 will flow downward to the bottom of the column 12 where a portion of them will be withdrawn through a pipe 13 by a pump 14 and pumped through a reboiling tube 16 which leads through the furnace 6 and thence 20 into the bottom of the fractionating column 12. Heat is imparted to this material which is passed through tube 16 into the column 12 to aid in the rectification step carried out therein. The 25 excess of this material which will accumulate in the bottom of the column 12 will be withdrawn through a pipe 18 in which is mounted a valve 19. This material and the liquid withdrawn through the pipe 21 will be passed therefrom through coolers to storage tanks, neither of which are 30 shown.

Liquids collected in the accumulator 22 will be delivered by a pump 30 through a pipe 29 having mounted therein a valve 31 into and through the entire conversion tube 5. A pipe 8 having mounted therein a valve 9 is connected into the pipe 29 and leads to an intermediate point in the conversion tube 5. In another method of operation by opening valve 9 and closing valve 31 the pump 30 will pump liquid from the accumulator 22 35 through pipe 29, into pipe 8, through valve 9 and thence through a later portion of the conversion tube 5. In this way this material which is still too volatile to be included in the motor fuel withdrawn from the column 12 through pipe 40 45 21 will be reprocessed in the conversion tube 5 and the maximum quantity of material suitable for use as motor fuel will be thus obtained.

It will be found desirable in some cases to add to the charge a quantity of comparatively less 50 volatile motor fuel as it will be found that such material will combine quite readily with the lighter constituents of the liquefied gases, and result in smaller fixed gas production.

In passing through the conversion tube 5 the 55 portion of the unstabilized charging stock which is too volatile to be included in motor fuel will undergo polymerization reactions and at least a part of this volatile material will be polymerized to less volatile liquids which may be satisfactorily 60 included in motor fuel. At the same time the remaining portion of the unstabilized charging stock which is already of suitable volatility for inclusion in motor fuel will be reformed and its anti-knock rating improved without substantially 65 changing its volatility characteristics.

In practicing my process the pressures maintained in the conversion tube 5 may be any pressures from atmospheric up to pressures of 10,000 pounds per square inch or above. The maximum 70 pressure limits being subject largely to the commercial availability of structural materials capable of withstanding such pressures. However, I find it more desirable to use pressures of at least 500 pounds per square inch and depending on the 75 type materials to be processed and the results

desired, I find pressures of around 3000 pounds per square inch particularly preferable.

Similarly, temperatures attained in the conversion tube will usually lie above 750° F. and often as high as 1150° F. or higher, this condition 5 also being subject to variation in stocks treated and results desired, as well as the pressures employed. Temperatures of 900° F. to 1100° F. are most usually employed.

A pressure of 100 to 500 pounds per square inch 10 will preferably be maintained in the fractionating column 12 and accumulator 22 and the inter-connecting pipe lines. However, either higher or lower pressures may be maintained in these parts of the equipment.

Through the use of this process unstabilized gasoline obtained from conventional natural gasoline plants or from a conventional gasoline plant used to separate gasoline from the cracked gases emanating from cracking stills may be stabilized 20 and not only may a larger yield of material of suitable volatility for motor fuels be obtained than has hitherto been possible but the final product will have a comparatively higher anti-knock rating.

While I have described in detail one method 25 of carrying out my new process, I do not wish to be limited to these particular details but intend to claim all the advantages which are inherent 30 in my new process.

I claim:

1. A process for converting and stabilizing gasoline containing substantial quantities of hydrocarbons too unstable to be incorporated in motor fuels, which comprises subjecting the said gasoline to conversion conditions such that at least a portion of said hydrocarbons which are too unstable to be incorporated in motor fuels are converted to materials which are sufficiently stable to be incorporated in motor fuels while simultaneously reforming that portion of the said gasoline which was sufficiently stable originally to be incorporated in motor fuels, rectifying the total converted material to obtain fixed gases, motor fuel and a fraction intermediate in volatility between the fixed gases and motor fuel, and returning the said intermediate fraction for reprocessing.

2. A process for converting and stabilizing gasoline containing substantial quantities of hydrocarbons too unstable to be incorporated in motor fuels which comprises subjecting the said gasoline to conversion temperatures of between 750° F. and 1150° F. whereby at least a portion of the said hydrocarbons which are too unstable to be incorporated in motor fuels are converted to materials which are sufficiently stable to be incorporated in motor fuels while simultaneously reforming that portion of the said gasoline which was sufficiently stable originally to be incorporated in motor fuels, rectifying the total converted material to obtain fixed gases, motor fuel and a fraction intermediate in volatility between the fixed gases and motor fuel, and returning the said intermediate fraction for reprocessing.

3. A process for converting and stabilizing gasoline containing substantial quantities of hydrocarbons which are too unstable to be incorporated in motor fuels, which comprises subjecting the said gasoline to conversion temperatures and to a pressure between 500 pounds per square inch and 3000 pounds per square inch, whereby at least a portion of the said hydrocarbons which are too unstable to be incorporated in motor fuels are converted to materials which are sufficiently sta- 75

- ble to be incorporated in motor fuels, while simultaneously reforming that portion of the original material which was sufficiently stable originally to be incorporated in motor fuels, rectifying the total converted material to obtain fixed gases, motor fuel and a fraction intermediate in volatility between the fixed gases and motor fuel and returning the said intermediate fraction for reprocessing.
- 10 4. A process for converting and stabilizing gasoline containing substantial quantities of hydrocarbons which are too unstable to be incorporated in motor fuels which comprises subjecting the said gasolines to a temperature between 750° F. and 1150° F. and a pressure between 500 pounds per square inch and 3000 pounds per square inch whereby at least a portion of the said hydrocarbons which are too unstable to be incorporated in motor fuels are converted to materials which are sufficiently stable to be incorporated in motor fuels while simultaneously reforming that portion of the said gasoline which was sufficiently stable originally to be incorporated in motor fuels, rectifying the total converted material to obtain fixed gases, motor fuel and a fraction intermediate in volatility between the fixed gases and motor fuel, and returning the said intermediate fraction for reprocessing.
- 15 5. A process for converting and stabilizing unstable gasoline containing substantial quantities of hydrocarbons which are too unstable to be incorporated in motor fuels, which comprises passing the unstable gasoline in a restricted stream through a heating zone and therein subjecting
- the same to temperatures between 750° F. and 1150° F. while maintaining the same under a pressure between 500 and 3000 pounds per square inch for a time sufficient to convert a portion of said hydrocarbons which are too unstable to be incorporated in motor fuels to materials which are sufficiently stable to be incorporated in motor fuels while simultaneously reforming that portion of the original material which was sufficiently stable originally to be incorporated in motor fuels, then introducing said stream into a rectification zone, subjecting the material in the rectification zone to a reflux condensate formed from a portion of said material and thereby fractionating stable motor fuel from material lighter and heavier than said motor fuel, and passing a portion of the last mentioned lighter material with the unstable gasoline through the heating zone.
- 20 6. A process according to claim 1, wherein the rectification takes place under a pressure between 100 pounds per square inch and 500 pounds per square inch.
- 25 7. A process according to claim 2, wherein the rectification takes place under a pressure between 100 pounds per square inch and 500 pounds per square inch.
8. A process according to claim 3, wherein the rectification takes place under a pressure between 100 pounds per square inch and 500 pounds per square inch.
- 20 9. A process according to claim 4, wherein the rectification takes place under a pressure between 100 pounds per square inch and 500 pounds per square inch.

- ble to be incorporated in motor fuels, while simultaneously reforming that portion of the original material which was sufficiently stable originally to be incorporated in motor fuels, rectifying the total converted material to obtain fixed gases, motor fuel and a fraction intermediate in volatility between the fixed gases and motor fuel and returning the said intermediate fraction for reprocessing.
- 10 4. A process for converting and stabilizing gasoline containing substantial quantities of hydrocarbons which are too unstable to be incorporated in motor fuels which comprises subjecting the said gasolines to a temperature between 750° F. and 1150° F. and a pressure between 500 pounds per square inch and 3000 pounds per square inch whereby at least a portion of the said hydrocarbons which are too unstable to be incorporated in motor fuels are converted to materials which are sufficiently stable to be incorporated in motor fuels while simultaneously reforming that portion of the said gasoline which was sufficiently stable originally to be incorporated in motor fuels, rectifying the total converted material to obtain fixed gases, motor fuel and a fraction intermediate in volatility between the fixed gases and motor fuel, and returning the said intermediate fraction for reprocessing.
- 15 5. A process for converting and stabilizing unstable gasoline containing substantial quantities of hydrocarbons which are too unstable to be incorporated in motor fuels, which comprises passing the unstable gasoline in a restricted stream through a heating zone and therein subjecting
- the same to temperatures between 750° F. and 1150° F. while maintaining the same under a pressure between 500 and 3000 pounds per square inch for a time sufficient to convert a portion of said hydrocarbons which are too unstable to be incorporated in motor fuels to materials which are sufficiently stable to be incorporated in motor fuels while simultaneously reforming that portion of the original material which was sufficiently stable originally to be incorporated in motor fuels, then introducing said stream into a rectification zone, subjecting the material in the rectification zone to a reflux condensate formed from a portion of said material and thereby fractionating stable motor fuel from material lighter and heavier than said motor fuel, and passing a portion of the last mentioned lighter material with the unstable gasoline through the heating zone.
- 20 6. A process according to claim 1, wherein the rectification takes place under a pressure between 100 pounds per square inch and 500 pounds per square inch.
- 25 7. A process according to claim 2, wherein the rectification takes place under a pressure between 100 pounds per square inch and 500 pounds per square inch.
8. A process according to claim 3, wherein the rectification takes place under a pressure between 100 pounds per square inch and 500 pounds per square inch.
- 20 9. A process according to claim 4, wherein the rectification takes place under a pressure between 100 pounds per square inch and 500 pounds per square inch.
